UNITED STATES PATENT OFFICE.

WILLIAM I. BUNKER, OF LA GRANGE, ILLINOIS.

DESIGN FOR A SADDLE-CUSHION.

SPECIFICATION forming part of Design No. 28,040, dated December 14, 1897.

Application filed November 1, 1897. Serial No. 657,114. Term of patent 14 years.

To all whom it may concern:

Be it known that I, WILLIAM I. BUNKER, a citizen of the United States, residing at La Grange, in the county of Cook and State of Illinois, have invented and produced a new and useful Design for Saddle-Cushions, of which the following is a specification.

In the accompanying drawings, Figure 1 is a perspective view showing the upper side of a cushion for bicycle-saddles illustrating my design; Fig. 2, a bottom view showing the under side of the cushion, and Fig. 3 a cross-section taken on line 3 of Fig. 1.

The leading feature of my design consists in a body having a narrow extending front or pommel portion and a broad rear or seat portion, the pommel portion and central part of the seat portion extending back therefrom

being on a plane lower than the side parts of the latter and having open cellular work on its lower side throughout substantially its entire area, the upper side being closed or covered.

A is the body portion; a, the front or pommel portion; a', the rear or seat portion; a², the depressed part extending back from the pommel through the seat portion, and B an edge or border surrounding the body portion, the whole presenting a harmonious and ornate figure, as shown in the drawings.

I claim—

The design for a saddle-cushion, substantially as shown and described.

WILLIAM I. BUNKER.
